CLAIM

The ornamental design for a needle for diagnostic kit, as shown and described.

DESCRIPTION

FIG. 1 is a front, top, and right side perspective view of a needle for diagnostic kit;

FIG. 2 is a rear, top, and left side perspective view of the needle for diagnostic kit of FIG. 1;

FIG. 3 is a front elevational view of the needle for diagnostic kit of FIG. 1;

FIG. 4 is a rear elevational view of the needle for diagnostic kit of FIG. 1;

FIG. 5 is a left side elevational view of the needle for diagnostic kit of FIG. 1;

FIG. 6 is a right side elevational view of the needle for diagnostic kit of FIG. 1;

FIG. 7 is a top plan view of the the needle for diagnostic kit of FIG. 1; and,

FIG. 8 is a bottom plan view of the needle for diagnostic kit of FIG. 1.

The broken lines in the drawings are for the purpose of illustrating portions of the needle for diagnostic kit that form no part of the claimed design.
